UNITED STATES PATENT OFFICE

102,972

DESIGN FOR A DISPLAY STAND

Raymond A. Hennings, New Orleans, La.

Application September 9, 1936, Serial No. 64,783

Term of patent 7 years

To all whom it may concern:

Be it known that I, Raymond A. Hennings, a citizen of the United States, residing at New Orleans, in the parish of Orleans and State of Louisiana, have invented a new, original, and ornamental Design for a Display Stand, of which the following is a specification, reference being had to the accompanying drawing, forming a part thereof.

I claim:

The ornamental design for a display stand, as shown.

RAYMOND A. HENNINGS.
